UNITED STATES PATENT OFFICE.

ARTHUR WILCOCK, OF LONDON, ENGLAND, ASSIGNOR TO R. CARRILLO & CO., OF NEW YORK, N. Y.

DESIGN FOR A FABRIC.

52,690.

Specification for Design.

Patented Nov. 12, 1918.

Application filed September 11, 1918. Serial No. 253,640. Term of patent 7 years.

To all whom it may concern:

Be it known that I, ARTHUR WILCOCK, a subject of the King of Great Britain, residing in London, E. C., England, have invented a new, original, and ornamental Design for Fabrics, of which the following is a specification, reference being had to the accompanying drawing, forming part thereof.

The figure is a plan view of a piece of fabric showing my new design.

I claim:

The ornamental design for a fabric, as shown.

ARTHUR WILCOCK.
